DESIGN FOR AN ELECTRIC RANGE

William James Russell and Donald L. Hadley,
Mansfield, Ohio, assignors to Westinghouse
Electric & Manufacturing Company, a corpora-
tion of Pennsylvania

Application September 16, 1937, Serial No. 71,648

Term of patent 7 years

To all whom it may concern:

Be it known that we, William J. Russell, a citizen of the United States and a resident of Mansfield, in the county of Richland and the State of Ohio, and Donald L. Hadley, a citizen of the United States and a resident of Mansfield, in the county of Richland and the State of Ohio, have invented a new, original, and ornamental Design for an Electric Range, of which the following is a specification:

Figure 1 is a perspective view of an electric range embodying our new design.

Fig. 2 is a view in front elevation of the design shown in Fig. 1; and,

Fig. 3 is a side elevational view of the design shown in Figs. 1 and 2.

The dominant features of our design reside in the portions shown in full lines.

We claim:

The ornamental design for an electric range, substantially as shown and described.

WILLIAM JAMES RUSSELL.
D. L. HADLEY.
